CLAIM

I claim the ornamental design for a battery, as shown and described.

DESCRIPTION

FIG. 1 is a perspective view of a battery, showing my new design;

FIG. 2 is another perspective view thereof;

FIG. 3 is a top view thereof;

FIG. 4 is a bottom view thereof;

FIG. 5 is a front view thereof;

FIG. 6 is a back view thereof;

FIG. 7 is a first side view thereof; and,

FIG. 8 is a second side view thereof.

The broken lines in the figures depict portions of the article which form no part of the claimed design.
